UNITED STATES PATENT OFFICE.

WASHBURN RACE, OF LOCKPORT, NEW YORK.

IMPROVEMENT IN SKATES.

Specification forming part of Letters Patent No. 44,115, dated September 6, 1861.

To all whom it may concern:

Be it known that I, WASHBURN RACE, of Lockport, in the county of Niagara and State of New York, have invented a certain new and useful Improvement in Skates; and I do hereby declare that the following is a full and exact description thereof, reference being had to the accompanying drawings, making part of this specification.

Figure 1 is a side elevation of my improved skate; Fig. 2, a central longitudinal vertical section thereof; Fig. 3, a vertical transverse section in the plane of line $x x$, Fig. 1.

Like letters of reference indicate corresponding parts in all the figures.

My invention consists of a bearing for securing the runner to the foot-piece, formed with a longitudinal dovetailed channel, which receives the top of the runner of corresponding shape, and provided with a vertical screw-hole, through which passes a screw from the top, projecting down into a notch in the top of the runner, by which means not only is the runner clamped firmly to the foot-piece, but the same is prevented from working endwise.

In the accompanying drawings, A represents the ordinary foot-piece, and B the cast-iron runner, which is secured to the foot-piece by means of bearings C C. I prefer to make the bearings circular, substantially of the shape shown, and they are sunk into the wood in such a manner as to firmly hold in place when secured by the means hereinafter described. In the lower portion of each bearing, below the wood and longitudinally of the skate, is made a dovetailed groove, a , Fig. 3, of sufficient depth to receive and hold firmly the top of the skate-runner, which is made concave or hollowing at the sides, to produce the corresponding wedging or beveling form, as shown at b . Vertically in the bearing is made a screw-hole, through which passes a screw, D or D', whose lower end projects and rests in a notch, c , made in the upper edge of the runner within the groove a , as shown most clearly in Figs. 2 and 3. The front screw, D, is provided with a rigid head, d , and screws down from the top, but the rear one, D', is simply a plain straight screw, which holds in the bearing C at the bottom while it projects above the foot-piece at the top, thus forming the heel-screw, and a loose jam-nut, d' , screws down over it, thus clamping the runner to

the foot-piece. By this means it will be seen that the heel-screw performs a double function—viz., it secures the runner in place and at the same time it may be adjusted up or down a greater or less height to adapt it to different-sized heels, or to compensate for the wear and enlargement of the hole in which it fits in the heel.

Among the advantages of this arrangement are the following:

First. The dovetailed groove a holds the wedging runner B in such a manner that the latter can be released only by sliding the bearing C endwise on the runner. It also braces it in the best manner against lateral strain. The parts are secured together much more strongly and effectively than they would be if a simple plane groove were employed, in which case the joint would be loose. The socket in the bed A, in which the bearing C fits, is made sufficiently deep to allow said bearing to be drawn up therein by the action of the screw in such a manner that the top edge of the runner will strike and clamp against the under side of the bed, thus tightening it in the dovetailed groove a so firmly that it cannot become displaced under ordinary circumstances. Such an effect I believe is entirely original with myself. In addition to this the runner is held the whole diameter or length of the bearing C by the bevel of the dovetail, so that a cast-iron runner is made as strong and safe as a steel one. The advantage of this extended hold of the bearing C on the upper edge of the skate over that device where the runner is held in a plane groove simply by a dovetail-headed screw notched into the top of the runner is obvious. In the latter case a cast-iron runner would be worthless, from the fact that the screw would break out at the first unusual strain.

Second. Thus secured in the dovetailed groove a of the bearing the runner is held against end motion, or from moving longitudinally by means of the notches c in the runner, in which rest the ends of the clamping-screws D D'. By this device of the dovetailed grooves and the notches the runner is held in position without peradventure of being displaced, while the means employed are of the simplest character.

I do not claim a plane groove in the bearing in which the runner rests, and a screw holding

the runner in place, with a jam-nut screwing on top, as I am aware that such a device has been before known; but

What I claim as my invention, and desire to secure by Letters Patent is—

The dovetailed groove *a* in the bearing *C*, and the notch *c*, in combination with the wedge-sided runner *B*, screw *D* or *D'*, and foot-piece *A*, substantially as and for the purpose herein set forth.

In witness whereof I have hereunto signed my name in the presence of two subscribing witnesses.

WASHBURN RACE.
